UNITED STATES PATENT OFFICE.

CARL S. FRANK, OF WICHITA, KANSAS.

INTERNAL-COMBUSTION HEATER.

1,172,348.

Specification of Letters Patent. Patented Feb. 22, 1916.

Application filed June 30, 1915. Serial No. 37,402.

To all whom it may concern:

Be it known that I, CARL S. FRANK, a citizen of United States, residing at Wichita, in the county of Sedgwick, State of Kansas, have invented new and useful Improvements in Internal-Combustion Heaters, of which the following is a description.

My invention relates to new and useful improvements in internal combustion heaters for stoves, furnaces, grates, or the like and more particularly to that class adapted for burning hydrocarbon gases and gas from alcohol, and my object is to provide a plurality of pipe sections for the reception of the liquids and gases, and inclose the same in a suitable housing whereby the entire mechanism may be readily introduced into the fire box of a stove or other convenient point.

A further object is to provide gas jets and so arrange the same that they will convert the liquids into gases while passing through the pipe sections.

A further object is to provide suitable expansion chambers to receive and store excess gases.

A further object is to provide suitable ventilating openings for the casing inclosing the pipes and burners. And a further object is to provide a generating chamber for superheating the pipe sections previous to admitting the gas generating fluid into the pipes.

Other objects and advantages will be hereinafter set forth and more particularly pointed out in the accompanying specification.

In the accompanying drawings which are made a part of this application, Figure 1 is a top plan view of the heating device with the cover therefor removed, and Fig. 2 is a vertical longitudinal sectional view therethrough as seen on line 2, 2 of Fig. 1.

Referring to the drawings in which similar reference numerals designate corresponding parts throughout the several views, 1 indicates a housing which is preferably rectangular in general outline and constructed of sheet metal, said housing having a removable cover 2, said cover having depending flanges 3 which engage the upper edge of the housing and hold the

cover in position thereon. Positioned at a suitable point within the housing 1 and above the lower edge thereof is a partition 4, which partition is supported on suitable brackets 5 carried by the walls of the housing, said partition being spaced from the walls of the housing to provide air passages 6, said air passages entirely surrounding the partition. Resting upon the partition 4 and adjacent the longitudinal edge thereof are tubes 7, said tubes being closed at both ends and are adapted to be used as storage tanks for the gases, said tubes having pipe sections 8 connected therewith, the upper ends of said pipe sections entering a tubular retort chamber 9 which is preferably positioned adjacent the upper edge of the housing 1 and substantially in line with the longitudinal axial center thereof and midway between the tubes 7. The tubes 7 and pipe sections 8 form supports for the retort chamber.

The retort chamber 9 is provided with cross heads 10 and immediately below the cross heads are positioned the tip ends 11 of burners 12, the pipe 13 of the burners extending into the retort chamber 9 at points beyond the cross heads 10, the upper ends 14 of the pipes 13 projecting through the retort chamber to a point adjacent the upper wall surface thereof so as to prevent the gas producing fluid from entering said pipe should an unusual quantity of the fluid be entered into the retort chamber. The ends 15 of the pipes 8 are likewise extended upwardly a distance above the lowermost surface of the retort chamber but said ends 15 are not extended as high as the ends 14, so that should the gas producing fluid be entered into the retort chamber faster than it is converted into gas, it will flow into the tubes 7 before reaching the top of the ends 14. The gas producing fluid is conducted into the retort chamber 9 through a feed pipe 16 which terminates in a T-head 17 beyond the wall of the housing 1, one terminal of the T-head having a pipe 18 attached thereto which leads to any form of supply tank (not shown), a valve 19 being employed to control the flow of the fluid into the feed pipe.

The opposite terminal of the T-head has an extension pipe 20 attached thereto which extends through one wall of the housing and into position over a generating pan 21, said pan being formed by depressing a portion of the partition 4, preferably at the longitudinal center of the partition, so that a quantity of the gas producing fluids may be entered into the pan and ignited to properly preheat the retort chamber 9 previous to admitting the gas producing fluid into the retort chamber.

In order to retain the fluid in the generating pan and prevent rapid consumption thereof when ignited, a section of asbestos 22, or other non-inflammable porous substance is placed into the generating pan which absorbs the fluid and causes the same to burn slowly. The admission of the fluid through the extension pipe 20 is controlled through the medium of the valve 23 intersecting the extension pipe 20 beyond the end of the T-head 17.

The number of cross heads 10 and burners 12 is determined by the size of the space to be heated as but one burner may be used or any number thereof used. It will also be understood that all the burners may be provided with a controlling valve 24, although in the present instance, but one of the burners is shown supplied with a valve.

The partition 4 is provided immediately below the burners with draft openings 25 and the side and end walls of the housing are likewise provided with vents 26 through which air may enter the housing and cause proper combustion of the gases below the retort chamber, these openings also allowing for expansion of the gases as well as the proper mixing of the air to complete the combustion.

In order to allow for the sudden expansion of the gases above the burners, the top of the cover 2 is bowed upwardly, as shown at 27 and said bowed up portions are provided with openings 28 and 29 which are arranged in series, any preferred number of the openings being employed.

In operation the valves 19 and 23 are opened and a quantity of gas producing fluid admitted into the generating pan 21 when the valves are again closed and the fluid ignited in the pan. The heat from the burning fluid will superheat the retort chamber 9 and when the gas producing fluid is introduced thereinto will convert the same into a gas so as to cause the same to flow through the burner, and when ignited at the tip end of the burner the flame therefrom will continue to generate gases so long as the valve 19 is open and the fluid entered into the retort chamber.

By elevating the ends of the various pipe sections entering the retort chamber to a point higher than the lowest level of the

retort chamber, the fluid entered into the retort chamber will be converted into gas before it reaches a height to enter the ends of the pipes under all ordinary circumstances and by providing the tubes 7 the gases, if produced faster than consumed, will enter said tubes and compress therein, thereby storing a sufficient amount of the gases to cause an even pressure through the burners and give a steady equalized flame. It will likewise be seen that the amount of heat produced can be readily regulated by turning off a portion of the burner, in which event the amount of gas producing fluid admitted into the retort chamber is accordingly reduced. It will likewise be seen that by positioning the partition 4 a suitable distance above the lower edge of the housing, the air will readily enter through the grates of the fire box in which the burner is positioned, and also by providing the various openings and vents, the proper amount of air will be entered into the housing to cause proper combustion of the gases, and it will likewise be seen that this device can be used in connection with any suitable form of furnace, stove, or other heating apparatus, or can be set up and used independently thereof if desired.

Having thus fully described my invention what I claim as new and desire to secure by Letters Patent is:—

1. A heater, comprising a retort chamber, cross heads connected to said retort chamber, means to convey gas producing fluid into said retort chamber, a pair of storage tubes in a plane below said retort chamber and on opposite sides thereof, pipe sections connecting said tubes with the retort chamber, the ends of the pipe sections projecting a distance into the retort chamber, and burners connected to said retort chamber, said burners having one of their ends entered in said retort chamber and extended upwardly to a point adjacent the top of said retort chamber, the opposite ends of said burners terminating below the cross heads.

2. A heater, comprising a retort chamber having cross heads in its length, means to convey a gas producing medium into the retort chamber, a burner adjacent each end of the retort chamber, one end of the burner entering said retort chamber and extending to a point adjacent the upper face thereof, the opposite ends of said burners terminating below said cross heads, and storage tubes connected to said retort chamber and forming a support therefor.

3. A heater, comprising a retort chamber, a pair of tubes below and on opposite sides of the retort chamber, pipes connecting said tubes with the retort chamber, said pipes and tubes forming a support for the retort chamber, a housing, a partition in the housing above the lower edge thereof, said par-

tion being spaced from the walls of the housing to provide air passages, a cover for said housing having upwardly bowed portions, said bowed portions having series of openings therethrough, and burners attached to said retort chamber.

4. In a heater, the combination with a retort chamber and burners attached thereto, of a housing, a partition in said housing positioned above the lower edge thereof and spaced from the walls of the housing to form a passage, and a cover having upwardly

bowed portions at a point above said burners, said bowed portions having openings therethrough.

15 In testimony whereof I affix my signature in the presence of two witnesses on this the first day of February, nineteen hundred and fifteen.
